Company, East Pittsburgh, Pa., a corporation
of Pennsylvania

Application November 6, 1941, Serial No. 417,934

5 Claims. (Cl. 62—115)

This invention relates to mechanical refrigeration apparatus and more especially to a method and a device for rapidly defrosting the cooling unit of such apparatus.

One object of the invention is to effect rapid defrosting of the evaporator of a compressor-condenser-evaporator type refrigerating system.

Another object of the invention is to effect defrosting of selected areas of an evaporator.

A further object of the invention is to defrost the shell of an evaporator without melting the ice stored in the evaporator.

A still further object of the invention is to provide a multiple valve for reversing the flow of refrigerant in a mechanical refrigerating system.

These and other objects are effected by my invention as will be apparent from the following description and claims taken in connection with the accompanying drawing, forming a part of this application, in which:

Fig. 1 is a schematic drawing of a refrigerating system embodying the defrosting mechanism of this invention the mechanism being shown in the position which produces refrigeration of the evaporator, and

Fig. 2 is similar to Fig. 1 but with the mechanism shown in the position which produces defrosting of the evaporator.

Referring now to the drawings, the reference numeral 10 designates a U-shaped evaporator such as customarily used in domestic refrigerators. The evaporator includes two refrigerated shelves 11 formed by brazing portions of a refrigerant-carrying tube 12 in undulated configuration to the bottom of the shelves 11. The tube thereafter communicates with the bottom of the hollow U-shaped evaporator 10. Refrigerant is normally supplied to the evaporator 10 through the tube 12, the refrigerant passing along the shelves 11, then to the bottom of the hollow U-shaped evaporator 10, and thereupon upwardly through both legs of the U-shaped evaporator to the refrigerant headers 13. The level of the liquid refrigerant is normally located in the headers 13 and the vapors are drawn from the headers 13 through a tube 14, through conduits 16 and 17 by a refrigerant compressor 15. The refrigerant compressor is driven by an electric motor 20 and both the compressor and the electric motor are enclosed in a hermetically sealed casing 18.

The electric motor 20 in the casing 18 is energized through lines 19 and 21 by means of the connecting lines 22 and 23. The connecting line

22 has a switch 24 included therein actuated by an expansible bellows 26 which is in communication with a bulb 27 through a tube 28. The bulb 27 contains a volatile liquid which causes the bellows 26 to expand and close the switch 24 whenever the temperature of the evaporator 10 rises above a predetermined limit.

The refrigerant vapor withdrawn from the evaporator 10 is compressed by the compressor 15 and passes through tubes 29 and 31 to a condenser 32 wherein the refrigerant vapor is liquified, and thereupon passes as a liquid through tubes 33, 34, 35, 36, and 37 to the aforementioned tube 12. Of these tubes, tube 35 is a flow restrictor such as a capillary tube. The above-described flow of refrigerant is indicated by the arrows of Fig. 1.

Fig. 2 shows the flow of refrigerant when the evaporator 10 is being defrosted. During the defrosting, the refrigerant is by-passed around the capillary tube 35 by tubes 38 and 39 so that the evaporator 10 is substantially at the same pressure as the condenser 32 and substantially no refrigerant liquid is formed. The flow of refrigerant vapor during the defrosting operation is from the compressor in the casing 18 through the tube 29, tube 41, tube 16, and tube 14 to the two refrigerant headers 13 from whence it flows downwardly through the two lengths of the U-shaped evaporator 10 and upwardly through tube 12, through tube 37, tube 38, tube 39, tube 33, through the condenser 32, through tube 31, and through tube 17 back to the compressor 15 in the sealed casing 18.

The refrigerant pumped into the evaporator 10 during the defrosting cycle is in the form of a vapor at the temperature of the compressor and condenser 32 both of which are at or above room temperatures. The relatively warm refrigerant vapor pumped reversely through the evaporator 10 forces the liquid refrigerant therein out through the tube 12 and through tubes 37, 38, 39, and 33, through the condenser 32, through tubes 31 and 17 into the sealed casing 18 where it remains. It will be observed that the shell of the U-shaped evaporator receives the warm refrigerant vapor first of all and will, therefore, be defrosted before the shelves 11 are defrosted.

The multiple valve mechanism of this invention which effects the reversal of refrigerant flow just described and the mechanism for actuating the compound valve mechanism will now be described. The valve mechanism comprises a hollow cylindrical valve body 42 and a valve stem 43 adapted by guides 44 and 45 for axial move-

ment within and longitudinally of the valve body 42. Two annular, spaced apart, and coaxial recesses 46 and 47 are provided adjacent one end of the valve body 42. The annular recess 46 forms two opposite-facing valve seats 48 and 49 and the annular recess 47 forms a similar pair of oppositely-facing valve seats 51 and 52. A valve disc 53 is secured to the valve stem 43 to lie in the recess 46 and seats selectively on the valve seats 48 and 49 depending upon the position of the valve stem 43. A similar valve disc 54 is secured to the valve stem 43 and lies in the annular recess 47 to seat selectively on the valve seat 51 or 52. The respective valve discs 53 and 54 are spaced to seat simultaneously on the valve seats 48 and 52 and likewise simultaneously on the valve seats 49 and 51.

A further valve seat 55 is formed in the cylindrical body 42 adjacent the other end thereof, and a valve disc 56 is secured to the valve stem 43 to engage the seat 55 simultaneously with the engagement of seats 48 and 52 by the valve discs 53 and 54, respectively. A disc 57 is secured to the valve stem 43 between the valve discs 54 and 56. A cylindrical flexible bellows 58 is secured at one of its edges to the disc 57 and the other of its edges is secured to an angular shoulder 59 formed in the interior of the cylindrical valve body 42. The valve seats 48, 52, and 55 and the flexible bellows 58 are of substantially the same diameter. The bellows 58 forms a seal between the valve stem 43 and the valve body 42.

It will be apparent from an inspection of Fig. 1 that when the valve member 43 is in the lower position, the refrigerant flowing from tube 29 is transferred to tube 31, that the by-pass, comprising tubes 38 and 39, around the capillary tube 35 is closed, and that the refrigerant issuing from tube 16 is transferred to tube 17. In like manner an inspection of Fig. 2 will disclose that when the valve stem 43 is in the upper position, the refrigerant issuing from the tube 29 is directed to flow through tube 41 and thence through tube 16, the refrigerant flowing from tube 37 is permitted to flow through the by-pass comprising tubes 38 and 39, and the refrigerant flowing from tube 31 is directed to flow through tube 17.

The movement of the valve stem 43 is effected by an electro-magnet 65 which actuates an armature 66 affixed to one end 67 of the valve stem 43 which end 67 projects through an opening which also constitutes the guide 45. A sealing cup 68 is interposed between the electro-magnet 65 and the armature 66 to effect a seal for the opening in the valve body 42 comprising the guide 45. The sealing cup 68 is brazed at its edges to the valve body 42 and preferably constitutes non-magnetic metal such as brass. When the electro-magnet 65 is energized, the armature 66 and the valve stem 43 is pulled to its upper position and when the electro-magnet 65 is deenergized a spring 69 moves the valve stem 43 and the armature 66 to its lower position.

The power required to actuate the valve stem 43 is not very great because the valve stem 43 and the valve discs 53, 54, 56, and the disc 57 and bellows 58 comprise a balanced valve system when the valve stem 43 and the structures connected thereto are at the lower position as shown in Fig. 1. Assuming that the compressor of the refrigerating system is in operation, the high pressure above the valve disc 53 is balanced by the high pressure below the valve disc 54 and likewise the high pressure above the disc 57 is

balanced by the high pressure below the valve disc 56. To insure such balanced action it is necessary that the sum of the effective areas of the valve discs 54 and 56 when seated on the valve seats 52 and 55, respectively, is equal to the sum of the effective area of the valve disc 53 when seated on the valve seat 49 and the effective cross-sectional area of the bellows 58. When the compressor of the refrigerating system is not in operation and also when the valve stem 43 is in the upper position as shown in Fig. 2, the pressures in all of the portions of the valve body 42 are substantially equal so that the valve system is also balanced during these conditions.

The electro-magnet 65 is energized periodically for a short period, preferably each night, by an electric clock mechanism 71, which clock mechanism 71 receives its energy from lines 19 and 21 through leads 72 and 73. The electric clock mechanism 71 is arranged to close a switch 74 located in a lead 75 which supplies the electro-magnet 65 with power from the line 21. Another lead 76 supplies the electro-magnet 65 with power from line 19. The electric clock 71 also closes a switch 77 lying in the lead 78 which shunts the switch 24 to insure operation of the refrigerating mechanism regardless of the position of switch 24 so that whenever the clock mechanism 71 raises the valve stem 43, the compressor pumps warm refrigerant vapor through the evaporator 10 to defrost the same.

It will be apparent from the above that this invention provides a method and means for rapidly defrosting an evaporator of a refrigerating system, that the shell portion of the evaporator is defrosted before the shelves of the evaporator are defrosted so that ice stored on the shelves will not melt if the defrosting period is not of too long a duration. It will also be apparent that this invention provides a novel valve structure by means of which this result can be accomplished.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In a defrosting valve for a compressor-condenser-evaporator type refrigerating system in which a fixed orifice controls the flow of refrigerant to the evaporator, the combination of a hollow valve body having two annular, coaxial, and spaced-apart recesses in the interior thereof, each of said annular recesses providing two oppositely-facing valve seats, an annular shoulder in said valve body coaxial with said annular recesses, said annular shoulder being spaced from said two spaced-apart recesses and providing an additional valve seat, a valve stem in said body adapted for longitudinal movement, three valve discs on said valve stem adapted to simultaneously seat respectively on said additional valve seat and on said valve seats facing in the same direction as said additional valve seat when the valve stem is in one position and two of said valve discs being adapted to simultaneously seat respectively on the remaining two of said valve seats when the valve stem is in another position, sealing means between the valve stem and the valve body located between the

valve disc adapted to seat on said annular shoulder and the annular recesses nearest to said annular shoulder, said valve body having a plurality of ducts communicating with the exterior thereof, one of said ducts communicating with the space between the annular shoulder and the end of said body beyond said shoulder, another communicating with the space between said shoulder and said seal, another communicating with the space between said seal and the annular recesses nearest to said seal and with the space beyond the annular recess farthest from said seal and the end of said body adjacent said last-mentioned recess, another duct communicating with one of said annular recesses at a point between the valve seats thereof, another duct communicating with the other of said annular recesses at a point between the valve seats thereof, and another of said ducts communicating with the space between said recesses.

2. The method of defrosting the evaporator of a compressor-condenser-evaporator refrigerating system having a restrictor for controlling the flow of refrigerant to said evaporator, said evaporator having portions primarily for the storage of frozen material and other portions primarily for maintaining an insulated space at low but above freezing temperatures, the flow of refrigerant during normal operation of said refrigerating system being from said first-named portions to said second-named portions, said method comprising rendering said restrictor ineffective and reversing the flow of refrigerant through said evaporator for a period of time sufficient to substantially defrost said evaporator but insufficient to melt substantial portions of the frozen material which may be stored in the portion of the evaporator provided for the same and thereafter again rendering said restrictor effective and resuming the normal flow of the refrigerant through the evaporator.

3. In refrigerating apparatus, the combination of a compressor, a condenser, a flow-restricting passage, and an evaporator defining an elongated conduit, tubing connecting said compressor, condenser, flow-restricting passage, and evaporator in normal operating relationship, wherein the refrigerant passes through the elongated conduit of the evaporator in one direction, a reversing valve and tubing connected to said apparatus, said reversing valve being movable selectively to two positions one of which produces flow of said refrigerant in said one direction through the elongated conduit of the evaporator and the other of which positions produces flow of said refrigerant through said

elongated conduit in a direction reversely to said one direction, a second valve, tubing connecting said second valve in parallel with said flow-restricting passage, and means interconnecting said second valve with said reversing valve to close said second valve when the reversing valve is positioned to direct the flow of said refrigerant through the elongated conduit of the evaporator in said one direction and to open

10 said second valve when said reversing valve is positioned to direct the flow of refrigerant through the elongated conduit of the evaporator in a direction reversely to said one direction of the refrigerant therethrough.

15 4. In refrigerating apparatus, the combination of a compressor, a condenser, an evaporator, a flow-restricting passage, a flow-reversing valve, tubing connecting said condenser, flow-restricting passage, an evaporator in series, additional tubing connecting said flow-reversing

20 valve with said compressor, condenser, and evaporator, in operating relationship whereby said reversing valve functions to direct the flow of refrigerant from the compressor selectively

25 either through the condenser and thereafter through the evaporator in one direction or through the evaporator in the opposite direction and thereafter through the condenser, a second valve, tubing connecting said second valve in parallel with said flow-restricting passage, said second valve being interconnected with said reversing valve to operate simultaneously therewith.

30 5. In refrigerating apparatus, the combination of a compressor, a condenser, an evaporator, a flow-restricting passage, a flow-reversing valve, tubing connecting said condenser, flow-restricting passage, and evaporator in series, additional tubing connecting said flow-reversing

35 valve with said compressor, condenser, and evaporator, whereby said reversing valve functions to direct the flow of refrigerant from the compressor selectively either through the condenser and thereafter through the evaporator or

40 through the evaporator and thereafter through the condenser, a second valve, tubing connecting said second valve in parallel with said flow-restricting passage, said second valve being interconnected with said reversing valve to close

45 when the reversing valve directs the flow of the refrigerant through the condenser and thereafter through the evaporator and to open when the reversing valve directs the flow of a refrigerant through the evaporator and thereafter

50 through the condenser.

GRAHAM S. McCLOY.

CERTIFICATE OF CORRECTION.

Patent No. 2,351,140.

June 13, 1944.

GRAHAM S. McCLOY.

It is hereby certified that error appears in the printed specification of the above numbered patent requiring correction as follows: Page 1, first column, line 41, before the words "the shelves" strike out "along" second occurrence; page 3, second column, line 19, claim 4, for "an" read --and--; and that the said Letters Patent should be read with this correction therein that the same may conform to the record of the case in the Patent Office.

Signed and sealed this 15th day of August, A. D. 1944.
